INVENTOR:

UNITED STATES PATENT OFFICE.

FRANK M. GILHAM, OF SAN FRANCISCO, CALIFORNIA, ASSIGNOR TO AUGUST BUERMANN, OF NEWARK, NEW JERSEY.

DESIGN FOR A BRIDLE-BIT.

SPECIFICATION forming part of Design No. 17,040, dated December 28, 1886.

Application filed November 30, 1886. Serial No. 220,322. Term of patent 14 years.

To all whom it may concern:

Be it known that I, FRANK M. GILHAM, a citizen of the United States, residing at San Francisco, in the county of San Francisco and State of California, have invented and produced a new and original Design for Bridle-Bits; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a side elevation of a cheek-piece of a bridle-bit embodying my design, and Fig. 2 is an edge view of the same attached to a bridle-bit in its proper position, these views being deemed sufficient to fully illustrate my design, the leading features of which consist in a bridle-bit in which the cheek-piece thereof presents the appearance of a human leg in outline.

In said drawings, A indicates the mouth-piece of a bit, and B cheek-pieces thereof. C is the lower extremity of the cheek-piece, which

presents the appearance or outline of a human leg, the outer face of said extremity being rounded or convexed when viewed in cross-section in resemblance to the shape of the human leg, the inner side, however, being preferably flat. The foot portion D, at the lower extremity of said cheek-piece, when said cheek-piece is viewed edgewise, as in Fig. 2, presents to the view a series of toe-shaped configurations E, while above the same, as at F, said foot portion is perforated.

What I claim as new is—

The design for a bridle-bit, which consists, essentially, of a bridle-bit having a mouth-piece, A, and cheek-pieces B, the latter in side elevation presenting to view leg and foot shaped extremities or portions C D, substantially as set forth.

In testimony that I claim the foregoing I have hereunto set my hand this 18th day of November, 1886.

FRANK M. GILHAM.
